UNITED STATES PATENT OFFICE.

WILLIAM MARCUS SIMPSON, OF PORTLAND, OREGON.

MULTIPLE-PROPELLER BOAT.

1,303,508.

Specification of Letters Patent. Patented May 13, 1919.

Application filed September 18, 1918. Serial No. 254,624.

To all whom it may concern:

Be it known that I, WILLIAM M. SIMPSON, a citizen of the United States, residing at Portland, in the county of Multnomah and 5 State of Oregon, have invented certain new and useful Improvements in Multiple-Propeller Boats; and do hereby declare the following to be a full, clear, and exact description of the invention, such as will enable others skilled in the art to which it 10 pertains to make and use the same, reference being had to the accompanying drawings, and to the letters and figures of reference marked thereon, which form a part of this 15 specification.

This invention relates to new and useful improvements in multiple propeller boats and comprises essentially in connection with the hull of the boat, pontoons held spaced 20 apart from the hull of the boat by downwardly curved arms and containing each an auxiliary propeller.

The invention comprises a simple and efficient device of this nature having various 25 details of construction, combination and arrangement of parts which will be herein-after full described, shown in the accompanying drawings and then specifically defined in the appended claim.

30 My invention is illustrated in the accompanying drawings which, with the letters of reference marked thereon, form a part of this application and in which:

Figure 1 is a top plan view of the boat 35 made in accordance with my invention.

Fig. 2 is a cross sectional view on line 2-2 of Fig. 1, and Fig. 3 is a side elevation.

Reference now being had to the details of 40 the drawings by letter:

A designates the hull of a boat which may be of any suitable size or shape modeled especially for high speed, and contains an electric power plant B. Downwardly curved 45 arms C are mounted upon either side of the

hull and each terminates at its outer end in a concaved portion which is fastened to the pontoons E, the said concaved portion being suitably braced as at D, and the arms are reinforced by bracket member C' having 50 flaring ends secured to the hull A and to the arms C. An electric motor H is adapted to be placed within each pontoon for the purpose of driving the propellers K mounted upon shafts I one within each pontoon, 55 power being derived from the power plant within the hull A.

By the provision of a boat made in accordance with my invention, it will be noted that the pontoons will act as stabilizers, 60 while accelerating power may be obtained from the motors therein, and by the manipulation of the latter the direction of the boat may be quickly controlled.

Suitable guns may be mounted upon the 65 hull of the boat and owing to the high speed which may be obtained by the craft same would be especially adapted for a submarine chaser.

What I claim to be new is:

A multiple propeller boat, comprising a 70 hull with downwardly curved arms having flaring ends secured to the opposite sides of the boat, brace members having flaring ends fastened to said arms and to the hull, the 75 outer ends of the arms having concaved braced portions, pontoons secured to said concaved portions of the arms, a motor within each pontoon, and a propeller connected to each pontoon and driven by said motors, 80 a power plant within the hull, and electrical connection between the same and the motors in the pontoons.

In testimony whereof I hereunto affix my signature in presence of two witnesses.

WILLIAM MARCUS SIMPSON.

Witnesses:

C. J. HAYES,
S. BRUM.
